DESIGN FOR A DOMESTIC REFRIGERATOR

Donald E. Dailey, Toledo, Ohio, assignor to Philco Corporation, Philadelphia, Pa., a corporation of Pennsylvania

Application June 12, 1941, Serial No. 101,433

Term of patent 14 years

To all whom it may concern:

Be it known that I, Donald E. Dailey, a citizen of the United States, residing in Toledo, county of Lucas, State of Ohio, have invented a new, original, and ornamental Design for a Domestic Refrigerator, of which the following is a specification, reference being had to the accompanying drawing, forming part thereof, in which the figure is a front perspective view of a domestic re-

frigerator, with the outer door in open condition for access, showing my new design.

The characteristic features of the design reside in the portions shown in solid lines.

I claim:

The ornamental design for a domestic refrigerator, substantially as shown and described.

DONALD E. DAILEY.
